UNITED STATES PATENT OFFICE.

JOHN W. MINOR, OF BROCKTON, MASSACHUSETTS.

*PICKET-POINTING MACHINE.

SPECIFICATION forming part of Letters Patent No. 469,390, dated February 23, 1892.

Application filed March 5, 1891. Serial No. 383,900. (No model.)

To all whom it may concern:

Be it known that I, JOHN W. MINOR, a citizen of the United States, residing at Brockton, in the county of Plymouth and State of Massachusetts, have invented a new and useful Picket-Pointing Machine, of which the following is a specification.

My invention relates to picket-pointing machines designed for the pointing of pickets for use in the making of fences and the like; and it has for its object the pointing of pickets in true curves of any desired length of radius within the limit of the machine in an expeditious and economical manner.

Figure 1 represents my picket-pointing machine in side elevation, a picket being shown to illustrate the method of picket-pointing. Fig. 2 is a plan of Fig. 1, with the exception that the picket is not shown. Fig. 3 is a sectional view of Fig. 1 on line 15 15, looking toward the rear of the machine. Fig. 4 represents, upon an enlarged scale, the sliding fulcrum in side elevation. Fig. 5 is a front elevation of Fig. 4, and Fig. 6 is a plan of Fig. 5. Fig. 7 represents the cutter-head, upon an enlarged scale, in plan, the lever-arms being shown in section. Fig. 8 is a sectional view of Fig. 7 on line 16 16, a portion of one of the lever-arms being shown. Fig. 9 represents one of the cutter-head disks in elevation, and Fig. 10 is a plan of Fig. 9.

The frame of the machine is composed of the main frame 20, supported by the legs 21, and it is provided with fulcrum-support 22, which is firmly fastened to the frame, the lever-chafing pieces 23, the adjustable head-block 24, and the chip-clearance space 25. The fulcrum-support 22 is provided with a vertical groove extending its entire length, as represented by dotted lines in Fig. 1, and the bolt 26, by means of which the fulcrum 27 is adjustably fastened to the fulcrum-support.

The fulcrum 27 is provided with the lugs 28, adapted to slide within the vertical groove of the fulcrum-support, slot 29, by means of which and the use of the bolt 26 the fulcrum may be adjustable secured to the fulcrum-support, the friction-boss 30, which is designed to lessen the rubbing friction of the lever-arms against the fulcrum, and the hole

31, through which the pivot-bolt 32 passes, which pivotally secures the lever-arms to the fulcrum.

The adjustable head-block 24 is provided with a groove, as represented by dotted lines 55 in Fig. 1, which is adapted to fit over the front portion of the main frame and to slide thereon, and the slot 33, by the use of which and the head-block bolt 34 the head-block may be adjustably secured to the main frame. 60

The cutting-lever 35 is composed of the two iron lever-arms 36 and the wood handle 37. The lever-arms are securely fastened to the handle by means of bolts, as represented, and the arms are provided with a series of holes 65 44, designed to receive the pivot-bolt 32. Between the lever-arms the cutter-head 38 is adjustably secured by means of the cutter-head bolt 39.

The cutter-head 38 is composed of the following: the two cutter-head disks 40, the cutter-knife 41, and the spring chip-breaker 42. These parts are all adjustably secured together and to the cutting-lever arms by means of the cutter-head shaft or bolt 39, 75 which passes through the lever-arms and disks. Each disk 40 is provided with the groove 43, designed to receive the cutter-knife. The cutter-head is constructed and the parts composing the head are assembled 80 as follows: The knife is placed in the grooves of the two disks, and they are then placed in position between the lever-arms. The cutter-head bolt is then passed through the arms and disks. The chip-breaker is then placed 85 upon the knife, and it is held in its position, as represented, by the cutter-head bolt. Then the cutter-head is adjustably secured in its position between the lever-arms by the cutter-head bolt.

It is essential in order to perform good smooth work in the pointing of pickets that the cutter-head should be adjustably secured between the lever-arms in such a manner as will permit a change in the angularity of the knife in its relation to the lever-arms and also that the knife may be longitudinally adjusted within the cutter-head, for the reason that the cutting-edge of the knife should be set at such a distance from the cutter-head bolt and lever-arms as will 90 95 100

prevent all chattering of the knife when cutting.

The operation of my picket-pointing machine is as follows: It being desired to point 5 a picket such as represented in Fig. 1, the picket is placed upon the main frame, as represented, where it is held, usually by the hand of the operator. It having been determined to give the picket a point such as represented by the full and dotted lines in Fig. 1, the fulcrum is then adjusted so that the distance from the pivot-bolt 32 to the edge of the cutting-knife will be equal to the radius of the desired arc of circle or curve of the point 10 of the picket. The head-block is then so adjusted that the cutting-knife will not cut below the center of the picket. The cutter-head is then adjusted as previously described. Then by operating the handle of the cutting- 15 lever in the direction as indicated by an arrow in Fig. 1 the knife will cut and point one-half of the picket on a curved or circular line, as represented by dotted curved line on Fig. 1. By turning the picket over and repeating 20 the cutting operation the other side may be cut, thereby completing the pointing operation.

By the use of the adjustable fulcrum and the lever-arms provided with the series of 25 holes a great variety of cuts may be made and also pickets of many different widths may be pointed having any desired curve within the limit of the machine, thereby giving a great range to the machine. When it 30 is desired to use any of the lower holes of the series of holes in the lever-arms, the fulcrum may be inverted, and when it is desired to use the upper holes of the series of holes in the

lever-arms the pivot-bolt may pass through the main frame.

It is essential in the rapid and effective operation of the machine for the use to which it is applied in order to produce a picket-pointing machine of great range in pointing pickets of all commercial widths that the several adjustments of the principal parts of the machine, as fully described, should be substantially as set forth. It is important that the main frame should be provided with the clearance-space to prevent the clogging of the 45 machine by the chips made in cutting.

What I claim as new, and desire to secure by Letters Patent, is—

1. In a picket-pointing machine, the cutter-head composed of the two grooved disks, a 50 knife, a chip-breaker, and a cutter-head shaft or bolt upon which the chip-breaker is mounted, in combination with the cutting-lever, substantially as described.

2. The main frame 20, provided with adjustable head-block 24 and the slotted fulcrum-support 22, upon which the adjustable fulcrum is mounted, in combination with the cutting-lever 35, provided with the adjustable cutter-head 38, which is composed of the cutter-head disks 40, cutter-knife 41, and chip-breaker 42, substantially as and for the purposes set forth.

In testimony whereof I have signed my name to this specification in the presence of 70 two subscribing witnesses.

JOHN W. MINOR.
